UNITED STATES PATENT OFFICE.

CHARLES A. ALDEN, OF STEELTON, PENNSYLVANIA.

GUARD-RAIL.

934,784.

Specification of Letters Patent. Patented Sept. 21, 1909.

Application filed July 10, 1909. Serial No. 506,927.

To all whom it may concern:

Be it known that I, CHARLES A. ALDEN, a citizen of the United States, residing at Steelton, in the county of Dauphin and State of Pennsylvania, have invented certain new and useful Improvements in Guard-Rails, of which the following is a specification.

This invention relates to guard rails for railroad track rails.

10 The object of the invention is to provide a guard rail of novel, simple and efficient construction, adapted to be supported by the track rail and having provision whereby the desired strength of the guard rail and the 15 excess metal to compensate for wear is attained with a minimum amount of metal, as will be hereinafter fully described and particularly pointed out in the claims.

20 In the drawings: Figure 1 is a side elevation of a section of a railroad rail provided with a guard rail embodying my invention. Fig. 2 is a transverse section thereof on line 2—2 of Fig. 1, showing the lower portion of a car wheel and its flange by dotted lines, 25 and showing also by a dot-and-dash line the contour of the upper portion of the track and guard rails after the same have been worn down by the engagement of car wheels and their flanges therewith.

30 A designates the track rail, and B the adjacent guard rail. The main rail, A comprises the base 3, the vertical web 4, and the head 5, and is of usual and well known construction.

35 In Fig. 2 there is shown by dotted lines the lower portion of a car-wheel and its flange in the position in which it runs normally upon the main or track rail A. The car wheel flange 7 runs in a flange-way 8 one 40 side wall of which is formed by the track rail head 5, as shown.

The guard rail B comprises the base portion 9, the substantially vertical web portion 10 rising from the base portion 9, the floor 45 portion 11 forming the floor of the flangeway 8 and supported by the web portion 10, and the head portion 12 rising from the floor portion 11 and forming the other side wall of the flange-way 8.

50 The web portion 10 is arranged directly below the flange-way 8 and in the same vertical plane therewith, as shown. The inner portion 13 of the floor portion 11 is fitted against the under side of the rail head 5 and the base portion 9 is made wider than the 55 web portion 10 and is seated upon the track

rail base 3, and the parts 9 and 13 are drawn firmly into engagement with the track rail A by bolts 14 which extend through the web portions 4 and 10 of the track rail A and 60 guard rail B respectively, and firmly secure the guard rail to the track rail.

The head portion 12 of the guard rail B is made wider than the web portion 10 and sufficiently so to compensate for the wear indicated by the dot-and-dash line in Fig. 2 without weakening the guard rail below its required strength.

In order to construct the guard rail B of the minimum amount of metal and yet provide for the wear thereof as hereinbefore described, without weakening the guard rail below the required strength, the location of the parts and the size thereof with respect to each other are very important, and particularly the location of the web portion 10 of the guard rail directly under the flangeway 8, as this enables the employment of a comparatively narrow web portion 10 and permits the floor portion 11 of the flangeway 8 to be worn deeply by the car wheel flange 7 without materially weakening the guard rail.

I claim:—

1. The combination with a track-rail comprising a base, a vertical web and a head forming one side wall of a wheel flangeway; of a guard-rail wholly supported by the track-rail and comprising a floor portion engaging the under side of the track-rail 85 head and extending outwardly therefrom and forming the bottom of said flangeway, a guard portion rising from the outer portion of the floor portion and forming the other side wall of said flangeway, a base portion supported on the base of the track-rail, and a web portion below and in the same 90 vertical plane with said flangeway and connecting said floor portion with said base portion; and means for securing said track-rail 95 and said guard-rail together.

2. The combination with a track-rail comprising a base, a vertical web and a head forming one side wall of a wheel flangeway; of a guard-rail comprising a floor portion 100 engaging the under side of the track-rail head and extending outwardly therefrom and forming the bottom of said flangeway, a guard portion rising from the outer portion of the floor portion and forming the 105 other side wall of said flangeway, a base portion supported on the base of the track-rail, and a web portion below and in the same vertical plane with said flangeway and connecting said floor portion with said base portion; and means for securing said track-rail, 110

and a web portion narrower than the guard portion below and in the same vertical plane with said flangeway and connecting said floor portion with said base portion; and 5 means for securing said track-rail and said guard-rail together.

3. The combination with a track-rail comprising a base, a vertical web and a head forming one side wall of a wheel flangeway; 10 of a guard-rail comprising a floor portion engaging the under side of the track-rail head and extending outwardly therefrom and forming the bottom of said flangeway, 15 a guard portion rising from the outer portion of the floor portion and forming the

other side wall of said flangeway, a web portion below and in the same vertical plane with said flangeway and connecting said floor portion with said base portion, and a base portion wider than said web portion 20 and formed on the bottom of said web portion and seated on the base of the track-rail; and means for securing said track-rail and said guard rail together.

In testimony whereof I affix my signature 25 in presence of two witnesses.

CHARLES A. ALDEN.
